UNITED STATES PATENT OFFICE.

OSBORNE E. QUINTON, OF CHICAGO, ILLINOIS.

VALVE-OPERATING MECHANISM FOR VAPOR-BURNERS.

1,391,976.

Specification of Letters Patent. Patented Sept. 27, 1921.

Application filed June 18, 1920. Serial No. 390,010.

To all whom it may concern:

Be it known that I, OSBORNE E. QUINTON, a citizen of the United States of America, residing at Chicago, in the county of Cook 5 and State of Illinois, have invented certain new and useful Improvements in Valve-Operating Mechanism for Vapor-Burners, of which the following is a specification, reference being had therein to the accompanying drawings.

Vapor burners, using hydrocarbon fuel and designed for paint burners, heaters, torches and such apparatus require intense heat. Valvular mechanism is employed for 15 controlling the supply of fuel to the burners and after some experience with this particular vapor burner it has been found defective in one particular, namely, that of permitting air to escape from the reservoir 20 when the reservoir is in one position.

The primary object of this invention is to provide a novel valvular construction which will at all times prevent air from escaping from the reservoir and thus maintain 25 the air within the reservoir for fuel feeding purposes, irrespective of the position in which the reservoir is placed.

A further object of my invention is to provide a valve actuating mechanism that 30 may be easily installed in a fuel reservoir and as readily removed therefrom, the valve operating mechanism being automatic to the extent of depending on gravity for opening and closing the valve, and the arrangement 35 of the mechanism is such that its operation is positive with a minimum amount of wear on the movable parts of the mechanism.

The above and other objects are attained 40 by a mechanical construction that will be hereinafter more fully described and then claimed, and reference will now be had to the drawings, wherein—

Figure 1 is a longitudinal sectional view 45 of a reservoir provided with a valve and operating mechanism in accordance with my invention;

Fig. 2 is a cross sectional view of the same;

Fig. 3 is a plan of a portion of the valve 50 operating mechanism, and

Fig. 4 is a side elevation of a conventional form of torch having a reservoir in accordance with this invention.

In the drawing, the reference numeral 1 55 denotes a fuel reservoir provided with a filling connection 2, normally closed by a

detachable cup 3, and this filling connection is located adjacent an end wall 4 of the reservoir. Adjacent the opposite end wall of the reservoir is a pump connection 5 for a conventional form of air pump 6 by which the air is supplied to the reservoir and placed under pressure therein, to force fuel from the reservoir, as will hereinafter appear.

The end wall 4 of the reservoir 1 has an air and liquid tight connection 7 for a burner connection 8 provided with a conventional form of needle valve 9 and the inner end of the connection has an extension 10 provided with a tubular bore 11 for a reciprocable tubular valve member 12 approximately the length of the reservoir 1. The extension 10 has a face thereof cut away or recessed, as at 13 and provided 15 with a valve seat member 14 at the inner end of the connection 8, which is adapted to communicate with tubular valvular member 12 when the end of said member engages the valve seat member 14, as shown in Fig. 80 1. The end of the tubular valvular member 12 may be conical or otherwise shaped so that it will positively engage the valve seat member 14 and close the communication between the connection 8 and that end of the 85 reservoir 1 containing the extension 10.

Mounted on the tubular valvular member 12 is a yoke 15 having side arms 16 engaging the side walls of the extension 10, and the arms 16 are notched, as at 17 and 90 18 with the notches 17 receiving side pins or stops 19 carried by the side walls of the extension 10. The pins or stops 19 will limit the longitudinal movement of the tubular valvular member 12 within the extension 10.

The notches 18 of the yoke 15 receives heads 20 of resilient arms 21, the arms being made of a single piece of material bent to provide a support for a weight 22, said 100 weight and said arms constituting a gravity actuated member which is supported relative to the extension 10 by side pins 23 of the arm 21 extending into the side walls of the extension 10, and the side walls of 105 said extension are beveled, as at 24, so that the arms 21 may be placed downwardly over the extension 10 and forced apart whereby the pins 23 may engage in the pockets or recesses provided therefor in the 110 side walls of the extension.

Slidable in the weight 22 is a bail 25 which

O. E. QUINTON.

VALVE OPERATING MECHANISM FOR VAPOR BURNERS.

APPLICATION FILED JUNE 18, 1920.

1,391,976.

Patented Sept. 27, 1921.

Fig. 1.

Inventor

Osborpe E. Quinton,

Attorneys

nected to said valve adapted to automatically actuate said valve to provide an outlet for fuel at the opposite end of said reservoir.

5. A reservoir as characterized in claim 4, wherein said means includes a weight, resilient arms connecting said weight to said valve, and means adapted to spring said arms by withdrawal of said means from said reservoir to release said arms relative to said 10 valve.

6. A reservoir for vapor burners adapted to contain a fuel under air pressure and provided with a filling connection, a burner connection at one end of said reservoir having 15 an extension in said reservoir, a tubular valvular member slideable in the extension of said burner connection and providing a constant outlet for fuel at one end of said reservoir and adapted to be shifted to provide 20 an outlet for fuel through said burner connection at the opposite end of said reservoir, and a gravity actuated device pivotally connected to the extension of said burner connection and adapted to shift said tubular 25 valvular member.

7. A reservoir as characterized in claim 6, wherein said device is insertible through the filling connection of said reservoir and detachably connected to the extension of said 30 burner connection.

8. The combination of a portable reservoir adapted to contain fuel under air pressure and provided with a filling connection, a burner connection at one end of said reservoir, constantly communicating with the opposite end of said reservoir and adapted to communicate with the burner connection end of said reservoir, and gravity means insertible through the filling connection of said 35

reservoir and detachably supported in the 40 transverse plane of the filling connection controlling the communication between said burner connection and its end of said reservoir.

9. The combination set forth in claim 8, 45 wherein said gravity means includes a weight adjacent to filling connection of said reservoir and adapted to swing from one side of the transverse plane of said filling connection to the other side thereof. 50

10. The combination with a reservoir having a filling connection, a burner connection and a valve in said reservoir controlling the manner in which said burner connection communicates with said reservoir, of a gravity device in said reservoir adapted to automatically operate said valve, said device comprising arms adapted to be sprung into engagement with said burner, connection and pivotally supported thereby in operative 55 relation to said valve a weight carried by said arms, and means carried by said weight adapted for separating said arms to release said device relative to said burner connection. 60

11. The combination set forth in claim 10, wherein the device as a whole is insertible through the filling connection of said reservoir and its operative relation with said valve is established by a yoke engaged by 65 ends of said arms. 70

In testimony whereof I affix my signature in the presence of two witnesses.

OSBORNE E. QUINTON.
